UNITED STATES PATENT OFFICE

99,854

DESIGN FOR AN ASH RECEIVER

Irving H. Chandler, New York, N. Y.

Application April 15, 1936, Serial No. 62,120

Term of patent 7 years

To all whom it may concern:

Be it known that I, Irving H. Chandler, a citizen of the United States, residing in New York, in the county and State of New York, have invented a new, original, and ornamental Design for an Ash Receiver, of which the following is a specification, reference being had to the accompanying drawing, forming part thereof.

The figure is a perspective view of an ash receiver showing my design.

I claim:

The ornamental design for an ash receiver as shown.

IRVING H. CHANDLER.
